OSCILLATING DEVICE

Henry Von Kohorn, New York, N. Y.

Application April 18, 1941, Serial No. 389,118

10 Claims. (Cl. 242—43)

The present invention relates to an improved means for producing an oscillating motion.

The main object of my invention is to provide an improved means for imparting an oscillating motion which oscillating motion has a minimum of pause or dead stop at that point where the direction of motion is reversed, which point occurs at the end of the stroke.

While the present invention is applicable to any devices or machines requiring an oscillating, swinging or reciprocating motion, I shall for the purpose of illustration, describe my invention as applied to an oscillating thread guide used in winding bobbins or the like, but it should be understood that I do not wish to be limited thereby.

In winding bobbins, the thread before being wound on the bobbin is usually led through a guide, which guide is reciprocated so that the bobbin may be uniformly wound. However, in the usual guide generally in use, the said guide is so reciprocated that at the end of the stroke there is a pause, during which time the guide reverses its direction. Because this pause is usually unduly long, the bobbin is not uniformly wound and bulges occur at each end of the bobbin. The disadvantages of these bulges are obvious.

Such bulges are undesirable and actually very harmful in the treatment of a thread or yarn on the bobbins, such as washing, drying, bleaching, dyeing, steaming and other operations. In view of the fact that at these bulges the thickness of the package of yarn is greater, the treating time must be based on the treating time required by the package at these bulges. While, for example, it may be sufficient to bleach a package of yarn of a definite thickness for two hours, the bulges which may have twice the thickness would require four hours in order to be fully bleached. But if the whole package is subjected to four hours of bleaching, most of the yarn will have been attached and destroyed by the action of the bleaching solution.

It is therefore the main object of my invention to provide a means which will wind a bobbin uniformly throughout, without the presence of any undesirable bulges.

Another object of my invention is to provide a means which may be easily and simply secured to the present types of winding apparatus, which means will remedy any bulges which might otherwise be formed on the wound bobbins.

Other objects of my invention will be set forth in the following description and drawing which

illustrate preferred embodiments thereof, it being understood that the above statement of the objects of my invention is intended generally to explain the same without limiting it in any manner.

Fig. 1 is a front view of thread guiding means as generally now in use;

Figs. 2 and 3 are front views of thread guiding means in different positions of the stroke, said thread guiding means embodying one embodiment of my improvement;

Fig. 4 is a different type of thread guiding means now in use;

Figs. 5 and 6 show my device as applied to thread guiding means illustrated in Fig. 3;

Figs. 7 and 8 illustrate another embodiment of my device;

Fig. 9 is a front view of still another embodiment;

Fig. 10 is a sectional view of the bobbin as presently wound;

Fig. 11 is a detailed section showing the end bulges usually formed on such a wound bobbin;

Fig. 12 is a sectional view of a bobbin wound with my improved means;

Fig. 13 is a diagrammatic view of a bobbin being wound with my improved means;

Fig. 14 is a side view of another embodiment of my device; and

Fig. 15 is a front view thereof.

Referring to the drawing, in the usual type of bobbin winding means, a bobbin 4 having a winding 5 is rotated about its longitudinal axis and a thread or yarn 14 is led through a guide member, which guide member is reciprocated along the length of the bobbin, thus depositing the thread along the entire outer face of the bobbin. A guide 8 is usually positioned at the end of a pendulum 7 or arm 13, which pendulum or arm is mechanically motivated so as to oscillate or reciprocate, the length of said oscillation being slightly less than the length of the bobbin to be wound. This oscillation is usually a simple harmonic motion, or at most a motion in which there is a substantial stop at both ends of the stroke, and it is quite obvious that due to this stop, since the bobbin rotates at a uniform speed, more thread will be wound at the end of the bobbin, thus causing the undesirable bulges 3.

I have found that by reducing the time of stop at the end of the stroke of said guide 8, the bulges 3 are entirely eliminated.

To accomplish this, guide member 11 having an arm 10 is pivotally mounted at a point 9, at

the lower end of the pendulum 7, said point 9 being at an intermediate point on the arm 10. At the other end of the arm 10 is a weight 12. I so mount the guide 11, arm 10 and weight 12 so that the guide 11 is at the lowermost position and at the lighter end of the arm 10, and the arm 10 is restricted to pivotally swing about point 9 within a predetermined arc.

The device would operate as follows:

As the bobbin is rotated and thread is fed through the guide 11, the pendulum 7 oscillates or swings back and forth (see Figs. 2 and 3). As it approaches the right uppermost point in its swing, the weight 12 is in lagging position and the guide 11 is in the leading position. When the pendulum 7 stops to reverse its motion, since the weight 12 has the motion imparted to it by the swinging pendulum 7, said weight 12 continues to move in the original direction, thus causing the arm 10 to rotate clockwise around point 9, and the guide 11 to move towards the left. It is obvious that this motion is directly reversed as the pendulum is at the other end of its swing. Thus, the time of stop of the guide member 11 is greatly reduced, therefore eliminating the uneven winding of the bobbin 4 and the resultant bulges 3.

In Figs. 5 and 6, I show an arrangement similar to that shown in Figs. 2 and 3, but as applied to a guide member which moves along the length of the bobbin by means of the reciprocating rod 13. The operation of the guide 11 mounted on the lighter end of arm 10, and weight 12 is similar to that shown in Figs. 2 and 3.

Figs. 7, 8 and 9 merely show my device illustrating how the swing of the arm 10 is limited.

In the embodiment shown in Figs. 7 and 8, the swinging pendulum 7 is a hollow tube and has pivotally mounted therein the arm 10, one end of said arm 10 having the thread guide 11 and the other top heavy end of said arm 10 having the weight 12. The side walls of said tube 7 limit the swinging movement of the arm 10.

In Fig. 9 I have shown a diagrammatic view of another embodiment of my device, in which a pair of stops 13 are provided at the lower end of the pendulum 7, said stops restricting the swing of the arm 10 therebetween.

In Figs. 14 and 15 I have shown still another embodiment of my device. In this embodiment, an arm 10 is pivotally mounted by means of a weight 9 within the forked end of the pendulum 7, the upper end of said arm being sufficiently weighted. Springs 16 are connected by means of pins 18 to each side of the swinging arm 10, the other ends of said springs being secured by means of pins 17 to the pendulum. These springs merely act as a buffer for the arm 10 so that when it does reverse its direction, there will be no jarring.

I have shown preferred embodiments of my invention, but it is obvious that numerous alterations and omissions may be made without departing from its spirit.

I claim:

1. A device of the character described, comprising an oscillating arm, means mounted on said arm and movable therewith, said means comprising a second arm, at least part of said second arm being movable relative to the said oscillating arm, said second arm being so mounted on the oscillating arm that part of said second arm moves in a direction opposite to that of the

oscillating arm when said oscillating arm approaches the end of its stroke, and travels in the same direction as the oscillating arm the remainder of the stroke.

5 2. A device of the character described, comprising an oscillating arm, a second arm pivotally mounted on said oscillating arm, said second arm being so mounted that the free end thereof will move in a direction opposite to that of the oscillating arm when said oscillating arm approaches the end of its stroke, and travels in the same direction as the oscillating arm the remainder of the stroke.

10 3. A device of the character described, comprising a swinging arm, a second arm pivotally mounted on said swinging arm, said second arm being freely rotatable about a point below its center of gravity.

15 4. A device of the character described, comprising a swinging arm, a second arm freely swingably mounted on said first swinging arm, said second arm being pivoted about a point below the center of gravity thereof, the swing of said second arm being restricted within a predetermined arc.

20 5. A device as claimed in claim 4, in which a thread guide member is provided at the lower free end of the second swinging arm.

6. A device of the character described, comprising a swinging tubular member, an arm pivotally mounted within said tubular member, said arm being freely swingable about a point below its center of gravity, the lower end of said arm projecting below the lower end of said tubular member.

30 7. A device as claimed in claim 6, in which a thread guide member is provided at the lower end of said rotatable arm.

8. A device of the character described, comprising a reciprocating arm, a second arm freely swingably mounted on said reciprocating arm, said second arm being rotatable about a point below the center of gravity thereof.

35 9. A device of the character described, comprising an oscillating arm, said oscillating arm having a forked end, a second arm pivotally mounted between the legs of said forked end, said second arm being swingable about an axis passing below the center of gravity of said second arm, a pair of springs, one end of each spring being secured to the upper end of the swingable arm, the other end of each spring being secured to the oscillating arm.

10. An oscillating device for producing an oscillating motion with reduced dead stop at the end of the stroke and change of direction, comprising at a point on said oscillating arm a second arm pivotally mounted on said oscillating arm about a point removed from the center of gravity

60 of said second arm, the lighter end of said second arm carrying a guide so that when at the end of the stroke of the oscillating arm said oscillating arm reverses its direction the heavier end of the second arm continues for a moment

65 on its original path due to its inertia, swinging around the point on which it is mounted and changing its relative position to the oscillating arm and therewith the position of the guide at the light end of the second arm abruptly and instantaneously giving it an impetus in the reversed sense and in a direction opposite to the original direction of the oscillating arm.

HENRY VON KOHORN.
